UNITED STATES PATENT OFFICE.

JOHN MANNING VAN HEUSEN, OF JAMAICA PLAIN, MASSACHUSETTS.

COLLAR BAND.

Application filed January 25, 1922. Serial No. 531,758.

To all whom it may concern:

Be it known that I, JOHN MANNING VAN HEUSEN, a citizen of the United States, residing at 33 Lakeville Place, Jamaica Plain, 5 in the county of Suffolk, State of Massachusetts, have invented certain new and useful Improvements in Collar Bands; and I do hereby declare the following to be a full, clear, and exact description of the invention, 10 such as will enable others skilled in the art to which it appertains to make and use the same.

The present invention relates to improvements in collar bands, and more particularly to improvements in collar bands such as are described in my Patent No. 1,277,788.

According to the present invention, the collar band is made of heavy fabric, such as a multiple ply interwoven fabric, and is provided with two thin extensions, one longer than the other, along one edge of the said collar band, by which the collar band may be attached to the shirt. The attachment of the collar band to the shirt with a collar band 25 woven in this way is greatly facilitated.

The collar band of the present invention may advantageously be attached to the shirt by placing the collar band on the shirt fabric with the longer thin extension coincident 30 with the edge of the shirt fabric, and securing the longer thin extension to the shirt fabric, for example, by stitching on a sewing machine. The remaining thin extension, that is, the shorter thin extension, will not 35 impede or obstruct in any way the sewing operation. The collar band may then be folded over into the plane of the shirt fabric, and the remaining free extension may be placed over the other side of the shirt 40 fabric and secured by stitching or other suitable means. This attachment requires only two operations and the collar band is firmly secured and furthermore presents a pleasing and finished appearance.

45 The fabric of which the collar band is made may advantageously be a two ply interwoven fabric or a three ply interwoven fabric. Fabrics of this kind have a considerable degree of inherent stiffness without the supplemental use of starch or other stiffening means. The fabric may be woven as a band of uniform width provided with a divided edge of the character above described, or it may be woven so that the outer 50 selvedge edge is given any desired contour. That is, the fabric may be woven of vary-

ing widths which give the edge of the fabric the desired shape so that the collar band will have a selvedge edge along its upper edge and will not require additional binding at 60 this portion. The fabrics as described may be woven either with a curvilinear weave or with the straight weave.

The fabric of which the collar bands are made may advantageously be provided with 65 transverse tubular portions separating the collar bands so that the fabric may be cut at these tubular portions and the divided edges thus formed turned in and secured in any appropriate manner. If 70 desired, a portion of the interweave may be omitted at the central portion of the collar band where the back buttonhole is placed, so that a pocket is formed at this portion, 75 one side of which may be used to protect the wearer from the base of the collar button.

The invention will be further described in connection with the accompanying drawings 80 illustrative of certain embodiments thereof, in which—

Fig. 1 is a perspective view showing the preferred embodiment of the invention;

Fig. 2 is a plan view of a strip of fabric 85 from which the collar bands may be cut;

Fig. 3 is an enlarged sectional view taken on the line 3—3 of Fig. 2.

Fig. 4 is an enlarged sectional view showing one attachment of the collar band to the shirt;

Fig. 5 is an enlarged sectional view taken on the line 5—5 of Fig. 1;

Fig. 6 is a plan view of a strip of fabric 90 from which the collar bands may be cut;

Fig. 7 is an enlarged sectional view taken on the line 7—7 of Fig. 1; and

Fig. 8 is an enlarged diagrammatical view showing one weave of the multiple ply fabric.

The fabric of which the collar band of 100 the invention is made may be, for example, a two ply interwoven fabric with or without an intermediate filling thread layer, or a three ply interwoven fabric. Fabrics of this kind, as above mentioned, have a considerable 105 degree of inherent stiffness, and collar bands made from this fabric will consequently retain or tend to retain their shape and set without starching.

One suitable weave of the multiple ply 110 fabric is illustrated in Fig. 8. This figure shows a two ply interwoven fabric with a

filling thread layer, two sets of warp threads 10 being interwoven with weft threads 11 to form two separate plies of fabric, and these plies being separated by an intermediate filling thread layer 13, and bound integrally together by the interweave threads 12.

The collar band fabric may, for example, be woven as a narrow fabric of uniform width as shown in Fig. 2. The fabric, shown in this figure, is provided with two thin extensions 5 and 6, the extension 5 being shorter than the extension 6. The thin extensions may be formed in the weaving operation by omitting the interweave threads 12 and also the filling threads 13 at the point where the extensions are woven, leaving the two separate plies of fabric.

The fabric may also, for example, be woven as shown in Fig. 6. That is, the fabric may be woven with a varying width such that the edge 14 of the fabric conforms with the desired contour of the collar band and is provided with a selvedge edge requiring no additional binding.

The fabric illustrated in Fig. 6 is woven with transverse tubular portions indicated at 7, these tubular portions separating the collar bands as they are woven in a continuous strip. These tubular portions may be cut, thus providing a divided edge on each end of the collar blank which may be turned in and secured by stitches 9, as indicated in Fig. 7. Also certain of the interweave threads may, if desired, be omitted in the back or central portion of the collar band, thus leaving the plies or layers of fabric separated and providing a pocket for the base of the collar button. One side of the said pocket may be provided with a button-hole through which the shank of the collar button will project. The fabric of Fig. 6 is provided with two integral extensions similar to those of Fig. 2, these extensions being indicated by the reference numerals 5^a and 6^a.

The collar band may advantageously be attached to the shirt in the manner illustrated in Figs. 4 and 5. As shown in Fig. 4, the collar band is placed on the shirt fabric 14 with the edge of the longer thin extension 6 even with the upper edge of the shirt fabric 14. The extension 6 and the shirt fabric may then be secured by the row of stitches 4^a. The collar band is then folded over into the plane of the shirt fabric, as shown in Fig. 5, and the extension 5 of the collar band is placed over the other side of the shirt fabric and secured by another row

of stitches 4^b. The collar band is thus securely attached to the shirt fabric by two simple operations and the collar band thus attached presents a pleasing and finished appearance. It will be noted that in securing the extension 6 to the shirt fabric by the stitches 4^a, as shown in Fig. 4, the extension 5, being shorter than the extension 6, does not obstruct the sewing operation in any way.

It will thus be seen that I provide a collar band, made of multiple ply interwoven fabric which has sufficient inherent stiffness, so that it will retain its shape and set without undue rigidity, and which may be attached to the shirt with ease and facility.

It will be understood that, while I have mentioned two ply and three ply interwoven fabrics, I do not limit myself to these fabrics, since a variety of fabrics and weaves may be used in connection with the invention.

I claim:

1. In the manufacture of shirts, the method of attaching a collar band made of relatively heavy unitary fabric having two integral extensions from the lower edge thereof, one of said extensions being longer than the other, which consists in placing the collar band and the shirt fabric together with the edge of the longer extension coincident with the edge of the shirt fabric, securing the said longer extension and the shirt fabric together; folding the neckband over so that it lies in the plane of the shirt fabric, placing the shorter extension over the other side of the shirt fabric and securing together the said shorter extension and the shirt fabric.

2. In the manufacture of shirts, the method of attaching a collar band made of multiple-ply interwoven fabric having two integral extensions from the lower edge thereof, one of said extensions being longer than the other, which consists in placing the collar band and the shirt fabric together with the edge of the longer extension coincident with the edge of the shirt fabric, passing a row of stitches through the longer extension and the shirt fabric, said row of stitches being beyond the edge of the shorter extension; folding the neckband over so that it lies in the plane of the shirt fabric, placing the shorter extension over the other side of the shirt fabric and passing a row of stitches through both the longer and shorter extensions and also through the shirt fabric.

In testimony whereof I affix my signature.
JOHN MANNING VAN HEUSEN.
